UNITED STATES PATENT OFFICE.

GEORGE E. DRUM AND JAMES H. SKITT, OF PHILADELPHIA, PENNSYLVANIA, ASSIGNEES TO SAID DRUM AND ROBERT P. SMITH, OF PHILADELPHIA, PENNSYLVANIA.

DYEING-MACHINE.

973,487.

Specification of Letters Patent. Patented Oct. 25, 1910.

Application filed August 23, 1910. Serial No. 578,510.

To all whom it may concern:

Be it known that we, GEORGE E. DRUM, a citizen of the United States, and JAMES H. SKITT, a subject of the King of Great Britain, residing at Philadelphia, county of Philadelphia, State of Pennsylvania, have invented certain new and useful Improvements in Dyeing-Machines, of which the following is a specification.

10 The object of our invention, as generally stated, is to provide in a dyeing machine, a novel, simple and efficient construction and organization of parts including a vat, a rotatable carrier provided with a compartment 15 or compartments to receive the articles to be dyed, means for actuating the carrier and means for causing the dyeing liquor to flow through the vat, whereby the dyeing liquor while being actuated to flow continuously 20 through the vat in one direction will be caused by a wall or walls of the compartment or compartments of the carrier to flow through the compartment or compartments in one direction in one position of the compartment or compartments of the carrier with respect to the path of the dyeing liquor and in another direction in another position of the compartment or compartments of the carrier with respect to the path of the dyeing 30 liquor.

The invention includes various novel features of construction and combinations of parts, all of which will be hereinafter fully described and particularly claimed.

35 In the drawings:—Figure 1 is a side elevation of our improved dyeing machine. Fig. 2 is a plan view thereof, partly broken away. Fig. 3 is a vertical section, on line 3—3 of Fig. 2. Fig. 4 is a vertical section, on line 4—4 of Fig. 2. Fig. 5 is an end elevation of the machine. Fig. 6 is a vertical section, on line 6—6 of Fig. 4. Fig. 7 is a detail in section of the latch or locking device for one of the doors forming one of 45 the inner walls of the carrier. Fig. 8 is a detail in section of the latch or locking device for one of the doors forming a part of the outer cylindrical wall of the carrier.

50 10 designates a vat adapted to contain the dyeing liquor. This vat 10 includes the side walls 11 and 12 forming supports for the vat and a curved or substantially semicircular wall 13 extending between and connected to the side walls 11 and 12. The vat 10 is

provided with a cover 14 which includes 55 side walls 15 and an upper wall 16. The cover 14 is provided with laterally disposed projecting arms 17 which are pivoted, as at 18, to brackets 19 on the top of the vat. The outer ends of the arms 17 are provided 60 with counterweights 20 for the cover 14, the counterweights 20 being adjustably mounted on the arms 17. It will thus be seen that the cover 14 may be readily moved on the pivot 18, to raise the cover from the top 65 of the vat to afford access to the interior thereof.

In order to raise the cover 14 from the vat 10 and lower it upon the same, we provide two hand levers 21, one on each side of 70 the vat. These levers 21 are secured to and project from a shaft 22 which extends through the side walls 11 and 12 of the vat. Each lever 21 is connected by a link 23 to a bracket on the arm 17 on the same side of 75 the vat. By moving either of the levers 21 by hand toward the left from the position shown, the cover 14 will be raised from the vat, and then by returning the levers 21 to the position shown, the cover 14 will be returned to the top of the vat.

Arranged within the vat 10 is a carrier 24 for the articles to be dyed, which carrier is of the following construction:—25 designates a centrally-arranged, horizontal shaft 85 on which are mounted end heads 26 and 27 forming the end walls of the carrier. The end heads 26 and 27 are connected by an outer cylindrical wall 28 and by an inner rectangular wall 29 inclosing a central 90 chamber 30 through which the shaft 25 extends. The space between the outer wall 28 and inner wall 29 is divided into four compartments 31 by partition walls 32, 33, 34 and 35 which extend between the end 95 heads and from the inner wall 29 to and beyond the outer wall 28, the outer edges of the walls 32, 33, 34 and 35 being adapted to move substantially in engagement with the inner face of the curved wall 13 of the 100 vat when the carrier is rotated about the axis of the shaft 25. The inner wall 29 is formed of screens, as shown, which are suitably secured at the four corners of the wall to angle irons 36 extending between the end 105 heads 26 and 27. The outer wall 28 includes four doors 37, one for each compartment 31, each door extending the length of

the carrier 24 between its end heads 26 and 27. Each door 37 is hinged, as at 38, to one of the partition walls of the carrier, and each door 37 is provided with notches 39 (Fig. 8) adapted to be engaged by latch members 40 to retain the doors in closed position, as shown. Each latch member 40 is slidingly fitted to a housing 41 on the outer wall 28 and is movable therein into and from engagement with the adjacent notch 39; and each latch member 40 is provided with an opening therein in which is arranged a spring 42, one end of which engages a pin 43 projecting from the wall 28 and the other end of which engages the member 40 and tends to project it into the adjacent notch 39. Each latch member 40 has a part 44 extending outside its housing 41 and provided with teeth which are engaged by the teeth of a toothed sector 45. The toothed sectors 45 of the latch members 40 for each door 37 are secured to a common shaft 46 having its bearings in parts of the wall 28; and each shaft 46 is provided with a suitable handle 47 whereby it may be turned to cause its sectors 45 to engage the teeth of their latch members 40 and withdraw them from engagement with the notches 39 in the adjacent door. It will thus be seen that by turning the shafts 46 to withdraw the latch members 40 from their notches 39 the doors 37 may be opened outwardly on their hinges 38 to afford access to the compartments 31. The ends of the latch members 40 which enter the notches 39 are beveled, as shown, whereby when the doors are closed they will engage the beveled ends of the members 40 and force them back against their springs 42, whereupon the springs 42 will project the members 40 into their notches 39 to maintain the doors 37 closed.

The main body of the entire outer wall 28 including the doors 37 is made in skeleton form, as shown, and covered by a screen 48 suitably secured to the skeleton body separate pieces of screen being secured to the doors 37 so as to open and close therewith. It will therefore be understood that the dyeing liquor within the vat 10 may flow freely through the outer wall 28 of the carrier 24 and into and out of the compartments 31. It will also be understood that the dyeing liquor may flow freely from one compartment 31 to another through the inner screen wall 29 and central compartment 30. The partition walls 32, 33, 34 and 35 are constructed of sheet metal in a manner to prevent the dyeing liquor from flowing therethrough and to control the flow of the liquor through the compartments 31 as will be hereinafter explained.

That portion of the partition walls 33 and 35 extending between the inner wall 29 and outer wall 28 of the carrier 24 constitutes

doors 94 and 95 respectively, hinged along their inner edges as at 96 and 97, to two of the angle irons 36. The outer portion of each door 94 and 95 is provided with notches 98 (Fig. 7) adapted to be engaged by latch members 99 to retain the doors 94 and 95 in the positions shown. Each latch member is slidingly fitted to a housing on the outer portions of the adjacent partition walls 33 and 35 and is movable therein into and from engagement with the adjacent notch 98; and each latch member 99 is provided with an opening or depression 48 therein into which extends one end of an arm 49. The arms 49 for the latch members 99 of each door 94 and 95 are secured to a common shaft 50 having its bearings in parts of the outer portions of the walls 33 and 35 of the carrier 24. Each shaft 50 is turned by springs 51 interposed between the outer wall 28 of the carrier 24 and arms 52 projecting from each shaft 50, the springs tending to turn the shafts in a manner to cause the arms 49 to project the latch members 99 into their notches 98. Each shaft 50 is provided with a suitable handle 53 by means of which it may be turned to cause the arms 49 to withdraw the latch members 99 from engagement with the notches 98 to permit the doors 94 and 95 to be moved on their hinges 96 and 97.

The ends of the latch members 99 that enter the notches 98 are beveled, as shown, whereby when the doors 94 and 95 are moved to the position shown in the drawings, said doors will engage the beveled ends of the members 99 and force them back against the action of the springs 51 whereupon the springs will turn the shaft 50 in a manner to cause the arms 49 to project the members 99 into their notches 98 to maintain the doors 94 and 95 in the position shown in the drawings.

The end heads 26 and 27 of the carrier 24 are provided with suitable brackets 54 and 55 respectively, by means of which the carrier 24 may be lifted from its position within the vat 10 and held in suspension for a purpose hereinafter described.

When the carrier 24 is within the vat 10, as shown in the drawings, the ends of the shaft 25 of the carrier rest within suitable bearings 56 and 57 secured to the side walls 11 and 12 respectively, of the vat. These bearings 56 and 57 are open at their tops to permit the ends of the shaft 25 to pass out of the same when the carrier 24 is lifted from the vat and to permit the ends of the shaft to enter the bearings when the carrier is lowered into the vat.

Supported on one side of the vat 10 and extending outwardly therefrom are two casings 60, each of which incloses a vertically-arranged chamber 61. The upper portion of each chamber 61 communicates with the vat 10 by means of a passageway 62 below

the top of the vat and above the horizontal plane of the center of the carrier 24. The lower portion of each chamber 61 communicates with a passageway 63 formed in the 5 wall 13 and communicating with the lower central portion of the vat 10, the passageway 63 extending the full width of the vat or substantially so.

10 Located in each chamber 61 is a horizontally-arranged propeller 64; and these propellers 64 are adapted to be actuated to drive the dyeing liquor down through the chambers 61 and passageway 63 and into the lower central portion of the vat 10, and at the 15 same time draw the dyeing liquor from the upper portion of the vat through the passageways 62 and into the chambers 61.

The propellers 64 are secured to the lower ends of vertically-arranged shafts 65 which are journaled in suitable bearings on the casings 60. The upper ends of the shafts 65 extend through the top walls of the casings 60 and are provided with beveled gear wheels 66 which coact with similar oppositely-disposed wheels 67 on a shaft 68 which is journaled in bearings 69 on the tops of the casings 60. It will thus be seen that when the shaft 68 is turned, the shafts 65 will be turned in opposite directions, and therefore the propellers 64 are made right and left, so that the dyeing liquor will be driven down through both chambers 61 when the shaft 68 is turned in one direction.

The shaft 68 is provided with a sprocket wheel 70 around which passes a sprocket chain 71 extending to and passing around a sprocket wheel 72 on a horizontal driving shaft 73 which is mounted in bearings 74 on the bottoms of the casings 60 and bearings 75 on the end walls 11 and 12 of the vat. One end of this driving shaft 73 is provided with a suitable pulley 76 by means of which power may be applied thereto to turn it and thereby actuate the propellers 64. The other end of the driving shaft 73 is provided with a beveled gear wheel 77 coacting with a similar wheel 78 on the upper end of an incline shaft 79 which is mounted to turn in a bearing 80 secured to the side wall 11 of the vat. The lower end of the shaft 79 extends into and is fitted to turn in bearings formed on a casing 81 which is supported by arms 82 projecting from a plate 83 secured to the side wall 11 of the vat 10. Secured to the shaft 79 within the casing 81 is a worm 84 coacting with a worm wheel 85 also located within the casing 81. This worm wheel 85 is secured to the outer end of a shaft 86 which extends through a bearing formed on the casing 81 and through a stuffing box 87 formed on the plate 83 and extending into the wall 11. The shaft 86 extends through the stuffing box 87 into the interior of the lower portion of the vat 10 and is provided on its inner

end with a pinion 88 in mesh with the teeth of a gear wheel 89 formed on the end head 26 of the carrier 24. It will thus be seen that when power is applied to the driving shaft 73 to actuate the propellers 64 to circulate the dyeing liquor, as previously described, the shafts 79 and 87 will be rotated in a manner to cause the pinion 88 to slowly rotate the carrier 24 within the vat 10. During the rotation of the carrier 24 the outer edges of the walls 32, 33, 34 and 35 move substantially in engagement with the inner curved face 90 of the wall 13 during their travel below the horizontal plane of the axis of the carrier, and also between the inner ends of the passageways 62 and 63 where they communicate with the vat 10. It will therefore be understood that when the parts are in the position shown in Fig. 3, the dyeing liquor will flow from the passageway 63 into the outer portion of the compartment 31 between the walls 34 and 35, thence to the central chamber 30 and thence from the inner portion to the outer portion of the compartment 31 formed between the walls 32 and 33. It will also be understood that immediately after the outer edge of the wall 34 leaves the passageway 63, the dyeing liquor will cease to flow inwardly through the compartments 31 between the walls 34 and 35 and will flow inwardly through the compartment 31 between the walls 33 and 34. It will also be understood that after the outer edge of the wall 32 leaves the passageway 62 the dyeing liquor will cease to flow outwardly through the compartment 31 between the walls 32 and 33 and will flow outwardly through the compartment 31 between the walls 32 and 35. It therefore follows that as the compartments 31 successively pass the passageway 62, the dyeing liquor will flow outwardly therethrough, and that as the compartments 31 successively pass the passageway 63, the dyeing liquor will flow inwardly therethrough, thus causing the dyeing liquor to flow through the compartments 31 in two directions during the actuation of the carrier 24, while the dyeing liquor is driven continuously in a single direction.

The pinion 88 is located with relation to the gear wheel 89 to permit the gear wheel 89 to move from engagement with the pinion 88 when the carrier 24 is raised from the vat and suspended in position above the same by any suitable means engaged with the brackets 54 and 55, as previously mentioned. When the carrier is thus suspended above the vat, the doors 37 may be opened, and the articles to be dyed placed within the compartments 31, after which the doors 37 may be closed and the carrier 24 lowered into the vat 10 and the gear wheel 89 re-engaged with the pinion 88. This being done, power is applied to the driving shaft 120 125 130

73, thereby causing the carrier 24 to rotate and the dyeing liquor to circulate, as previously described.

The rotation of the carrier 24 tumbles the 5 articles to be dyed within the compartments 31, which, together with the dyeing liquor flowing through the compartments 31 in different directions at different times, causes the articles to be dyed to be thoroughly sub- 10 jected to the action of the dyeing liquor. After the articles to be dyed have been thus subjected to the dyeing liquor a sufficient length of time, the carrier 24 is again raised from the vat 10 by any suitable means en- 15 gaged with the brackets 54 and 55 and transferred to a suitable point of discharge for the articles contained within the compartments 31, after which the doors 37 of the two lower compartments 31 may be 20 opened to permit the articles to be discharged from the lower compartments, and the doors 94 and 95 may then be opened to permit the articles in the two upper compartments to be discharged or removed 25 from the carrier through the two lower compartments.

We claim:—

1. In a dyeing machine, the combination of a vat; walls forming a passageway leading to and communicating with the vat at 30 two different points; means for causing dyeing liquor to flow through said passageway and said vat; a rotatable carrier within said vat, said carrier including walls forming a 35 compartment to receive the articles to be dyed, and the walls of the compartment having openings therein; and means for actuating the carrier; the walls of the compartment causing the dyeing liquor to flow 40 through the compartment in one direction when the carrier is in one position and to flow through the compartment in a reverse direction when the carrier is in another position.

45 2. In a dyeing machine, the combination of a vat; walls forming a passageway leading to and communicating with the vat at two different points; means for causing dyeing liquor to flow through said passageway and 50 said vat; a rotatable carrier within said vat, said carrier including walls forming a compartment to receive the articles to be dyed, and the walls of the compartment having openings therein; and means for actuating 55 the carrier; one wall of said compartment moving substantially in engagement with a wall of the vat between said points during the actuation of the carrier, and the walls of the compartment causing the dyeing liquor 60 to flow through the compartment in one direction when the carrier is in one position and to flow through the compartment in a reverse direction when the carrier is in another position.

65 3. In a dyeing machine, the combination

of a vat; walls forming a passageway leading to and communicating with the vat at two different points; means for causing dyeing liquor to flow through said passageway and said vat; a rotatable carrier within said 70 vat; and means for actuating the carrier; said carrier including walls dividing the carrier into a plurality of compartments to receive the articles to be dyed, said compartments communicating with each other 75 at the central portion of the carrier and communicating with the vat at the outer portion of the carrier, the outer portions of said walls moving substantially in engagement with a wall of the vat through a portion 80 of their path of travel during the actuation of the carrier, and the walls of the compartments causing the dyeing liquor to flow through said compartments successively first in one direction and then in a 85 reverse direction.

4. In a dyeing machine, the combination of a vat; walls forming a passageway leading to and communicating with the vat at two different points; means for causing dyeing liquor to flow through said passageway and said vat; a rotatable carrier within said 90 vat; means for actuating the carrier; said carrier including walls dividing the carrier into a plurality of compartments to receive 95 the articles to be dyed, said compartments communicating with each other at the central portion of the carrier and communicating with the vat at the outer portion of the carrier, the outer portions of said walls 100 moving substantially in engagement with a wall of the vat through a portion of their path of travel during the actuation of the carrier, and the walls of the compartments causing the dyeing liquor to flow through 105 said compartments successively first in one direction and then in a reverse direction, a hinged door for each compartment; and means for holding each door in its closed position.

5. In a dyeing machine, the combination of a vat; walls forming a passageway leading to and communicating with the vat at two different points; means for causing dyeing liquor to flow through said passageway 115 and said vat a rotatable carrier within said vat; and means for actuating the carrier; said carrier including walls forming two adjacent compartments divided by a partition wall to receive the articles to be dyed, 120 said partition wall moving substantially in engagement with a wall of the vat between said points during the actuation of the carrier and said partition wall controlling the direction of flow of the dyeing liquor.

6. In a dyeing machine, the combination of a vat; walls forming a passageway leading to and communicating with the vat at two different points; the vat being provided with a curved wall between said points; 130

means for causing dyeing liquor to flow through said passageway and said vat; a rotatable carrier within said vat, said carrier including walls forming a compartment 5 to receive the articles to be dyed, and the walls of the compartment having openings therein; and means for actuating the carrier; one wall of said compartment moving substantially in engagement with said 10 curved wall through a portion of its path of travel during the actuation of the carrier and said partition wall controlling the direction of flow of the dyeing liquor.

7. In a dyeing machine, the combination 15 of a vat; walls forming a passageway leading to and communicating with the vat at two different points; the vat being provided with a curved wall between said points; means for causing dyeing liquor to flow 20 through said passageway and said vat; a rotatable carrier within said vat, said carrier including walls forming a compartment to receive the articles to be dyed, and the walls of the compartment having openings 25 therein; and means for actuating the carrier; said carrier including walls forming two adjacent compartments divided by a partition wall to receive the articles to be dyed, said partition wall moving substantially in engagement with said curved wall through a portion of its path of travel during the actuation of the carrier and said partition wall controlling the direction of flow of the dyeing liquor.

8. In a dyeing machine, the combination 35 of a vat; walls forming a passageway leading to and communicating with the vat at two different points; the vat being provided with a curved wall between said points; means for causing dyeing liquor to flow 40 through said passageway and said vat; a rotatable carrier within said vat; and means for actuating the carrier; said carrier in-

cluding end heads, an outer wall extending between said end heads around the outer 45 portions thereof and partition walls dividing the space within said outer wall into compartments to receive the articles to be dyed, said compartments communicating with each other at the central portion of the 50 carrier, said outer wall including screens, said partition walls moving substantially in engagement with said curved wall through a portion of their path of travel during the actuation of the carrier and said partition 55 walls controlling the direction of flow of the dyeing liquor.

9. In a dyeing machine, the combination of a vat; walls forming a passageway leading to and communicating with the vat at 60 two different points; the vat being provided with a curved wall between said points; means for causing dyeing liquor to flow through said passageway and said vat; a rotatable carrier within said vat; and means 65 for actuating the carrier; said carrier including end heads, an outer wall extending between said end heads, an inner wall extending between said end heads and inclosing a central chamber and partition walls 70 dividing the space between said outer and inner walls into compartments to receive the articles to be dyed, said outer and inner walls including screens, said partition walls moving substantially in engagement with 75 said curved wall through a portion of their path of travel during the actuation of the carrier and said partition walls controlling the direction of flow of the dyeing liquor.

In testimony whereof we affix our signatures in the presence of two witnesses.

GEORGE E. DRUM.
JAMES H. SKITT.
